UNITED STATES PATENT OFFICE

NORMAN BLYTHE BRALY, OF REDWOOD CITY, CALIFORNIA

ILLUMINATED MIRROR

Application filed December 8, 1928. Serial No. 324,677.

The present invention relates to mirrors of the type in which the user thereof is illuminated.

The object is to provide a relatively simple and very compact structure that is adaptable for domestic use and may be made of a portable character.

In the accompanying drawings:

Figure 1 is a front elevation of the preferred embodiment of the invention, partially shown in section.

Figure 2 is a side elevation of the same, partially in section.

Figure 3 is a detail sectional view on the line 3—3 of Figure 1.

Figure 4 is a detail sectional view on the line 4—4 of Figure 1.

In the structure disclosed, a casing is employed that is preferably of sheet metal, and consists of a back wall 5 and an annular side wall 6. The front end of the casing is thus open, and fitted across said open end and bearing against the front edge of the side wall 6 is a reflecting sheet 7 that may be an ordinary silvered mirror glass. The sheet 7 is held in place by a retaining ring 8 that surrounds the side wall 6 of the casing and is held in place by suitable screws 9. This ring has an inturned flange 10 that overlies the margin of the disk or sheet 7 and thus securely holds it in place.

The ring 8 furthermore has at its rear end an outturned annular channeled or dished flange 11 that is faced forwardly and surrounds the mirrored body. In the channel is placed an electrical gas or vapor lamp 12 that may be of any well-known type. It is understood of course that the tube 12 is of glass and is filled with a gas or vapor which may be made luminous by an electrical current passed therethrough. To this end the terminals of the tube are turned inwardly as shown at 13 and extend into the casing where they are attached to electrode containers 14. A lead 15 to the electrodes in the containers may be provided with a plug 16 for engagement in an ordinary electrical socket element. The tube 12 is held in place by any suitable means, as for example, hooks 17 which pass through the channelled flange 11.

The mirror may be supported in any desired manner. Thus in the present embodiment, a yoke 18 carried by a standard 19, has its terminals pivotally mounted at 20 on opposite sides of the flange 11.

With this structure, when the tube 12 becomes a luminary by making the gas therein luminous through the supply of an electrical current to the terminals in the containers 14, the light will be thrown forwardly on all sides of the mirror and to the face of a person looking into the glass. A handy, compact and attractive structure is thereby produced.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim, is:

1. An illuminated mirror, comprising a casing, a reflecting sheet on the front thereof, a retaining ring for the reflecting sheet overlying the margins of the reflecting sheet and surrounding the casing and detachable therefrom and from the reflecting sheet, and illuminating means carried by the ring.

2. An illuminated mirror comprising a casing, a reflecting sheet located thereon, a retaining ring for the sheet detachably fitted on and surrounding the casing and having an open front channeled portion, said retaining ring overlying the margins of the reflecting sheet, and an illuminating means in the channel.

3. An illuminated mirror, comprising a casing having a mirror on its front wall, a retaining ring for the mirror detachably fitted to and surrounding the casing and having an inturned flange overlying the mirror and an outstanding forwardly faced channelled flange, a luminary of tubular form located in the channel, and means in the casing for causing the luminary to become active.

4. An illuminated mirror comprising a casing having a side wall, a reflecting sheet on

the front of the casing, a ring fitted on and surrounding the side wall of the casing and having an outstanding flange on its rear portion, and illuminating means located in front of said flange.

5. An illuminated mirror comprising a casing having a side wall and an open front, a reflecting sheet across said open front, a ring fitted on and surrounding the side wall and having an inturned retaining flange at its front edge overlying the reflecting sheet and having an inturned channeled flange at its rear edge, and an illuminating means in the channel of the latter flange.
- 10

15 In testimony whereof, I affix my signature.
NORMAN B. BRALY.
